CLAIM

The ornamental design for a baby bath seat as shown and described.

DESCRIPTION

FIG. 1 is a perspective view of baby bath seat showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partial enlargement view thereof;

FIG. 10 is a partial enlargement view thereof;

FIG. 11 is another perspective view thereof, shown in a different configuration; and,

FIG. 12 is a partial enlargement view thereof.

The evenly spaced broken lines in the drawings depict portions of the baby bath seat that form no part of the claimed design.

The dash-dot-dot broken lines in the drawings illustrate a boundary of the claimed design and form no part thereof.

The dash-dot broken lines showing the enlargements in FIGS. 1, 2, 3, 9, 10, and 12 form no part of the claimed design.

1 Claim, 12 Drawing Sheets
